CLAIM

The ornamental design for a portable disc jockey ("DJ") booth, substantially as shown and described.

DESCRIPTION

FIG. 1 is a front perspective view of a portable DJ booth;
FIG. 2 is a front view thereof;

FIG. 3 is a left view thereof;

FIG. 4 is a right view thereof;

FIG. 5 is a top view thereof;

FIG. 6 is a bottom thereof;

FIG. 7 is a rear view thereof; and,

FIG. 8 is a partial enlarged view illustrating box 8 of FIG. 1.

The broken lines in the drawings represent unclaimed environmental subject matter and form no part of the claim.
